UNITED STATES PATENT OFFICE.

GEORGE MITCHELL, OF DENVER, COLORADO.

DEVICE FOR REMOVING AND REPLACING ENGINE VALVES.

Application filed April 14, 1924. Serial No. 706,335.

My invention relates to a device for removing and replacing the spring-pressed intake and exhaust valves of internal combustion engines and the primary object of 5 the invention is to provide a simple contrivance which facilitates the removal and replacement of both the valves and the springs employed to control the supply and exhaust of motive fluid in the operation of 10 explosion engines of the type commonly used on motor-driven vehicles.

A further object of the invention is to provide in a device of the above described 15 character, a system of levers which permit of its convenient application to engines in which the valves are not accessible to ordinary lifting means and which effects the operation of the device with a moderate expenditure of manual force.

20 An embodiment of the invention has been illustrated in the accompanying drawings in which like characters of reference designate corresponding parts throughout the several views and in which

25 Figure 1 represents a front view of the valve casing of an internal combustion engine showing the improved lifting device in an operative position;

30 Figure 2, a section taken on the line 2—2, Figure 1, illustrating the device in a position for compression of the springs in order to replace the pins with which they normally engage;

35 Figure 3, a similar section showing the device in the position it occupies after the springs of the valves are compressed;

Figure 4, a top view of the spring-engaging member of the device;

40 Figure 5, a fragmentary underneath view of the same member;

Figure 6, a fragmentary sectional view showing said member in the position it occupies prior to the compression of the springs in replacing the valves, and Figure 45 7, a fragmentary edge view of the slotted spring-engaging member.

Referring more specifically to the drawings, my improved valve removing and replacing device comprises a plate 5 which in the operation engages the cups 6 in which the lower ends of the valve springs 7 are seated.

45 The plate has a plurality of equidistant slots 8 which are open in a longitudinal edge thereof to embrace the stems 9 of the valves 10 in the operation of the device, and the plate has furthermore a centrally disposed

upstanding arm 12 formed integrally at right angles to the upper side thereof for its connection with the lever system by which the springs engaged by the member 5 are 50 compressed.

The lever system above referred to consists of an upwardly bent lever 13 pivotally connected at the upper end of the arm 12, an operating handle 14 pivotally attached at 55 the outer extremity of the lever and an angular prop 15 pivotally connected with the lever between its extremities to provide a fulcrum for the operation of the lever, by engagement with a bottom of the valve casting 16 of the engine.

The slots 8 in the spring-engaging plate have substantially parallel edges which are beveled on the underside of the plate as at 57 to permit of the insertion of the plate between the springs and the recessed guide-bosses 18 on the bottom of the crank case, in which the lower ends of the valve stems are normally supported.

60 The springs which function to hold the valves of the engine to their seats, are coiled around the valve stems between the top of the valve casing and pins 19 which extend through transverse apertures in the lower portions of the stems as shown at the left-hand side of Figure 1.

In order to remove the valves and the springs, the pins are withdrawn from their apertures and to subsequently replace the pins the springs must be compressed against 65 the top of the valve casing until their lower ends are above the apertures of the stems.

70 My invention is particularly adapted to perform both functions of removing and replacing the valves and the springs in the following manner.

75 In order to permit of extracting the pins preparatory to removing the valves, the plate is placed beneath the cups in which the springs are seated, with its arm extending upwardly and the prop which is notched at its lower end is placed in engagement with the rounded front edge of the bottom of the crank case as shown in Figures 2 and 3 of the drawings.

80 The operating handle 14 is now moved to a position in substantial alinement with the fulcrum of the lever and the end of which it is attached, and by a quick downward movement of the handle the lever is caused 85 to turn about its fulcrum, thereby lifting the plate and compressing the springs as il-

lustrated in Figure 3. The pins 19 are now withdrawn and the valves can be removed while the springs are held in place by the locking action of the lever 13 in its adjusted 5 position.

To remove the springs from the crank case, the plate 5 is lowered by a reversed movement of the lever and withdrawn after the springs are brought in engagement with 10 the recessed bosses 18 which guide the lower ends of the valve stems in their upward motion.

To restore the valves and the springs to their normal co-operative position, the 15 springs are first placed in the same position they occupied after the plate was withdrawn as shown in Figures 1 and 2, and the plate 5 is then inserted between the bosses and the cups which support the lower ends of the 20 springs as indicated in Figures 2 and 6, and since this action requires a slight compression of the springs, the bevels 17 on the underside of the plate perform the important 25 and essential function of wedges which gradually lift the cups and thereby cause the plate to enter between them and the bosses with little effort on the part of the operator.

After the plate is thus positioned the prop 30 is again placed in engagement with its support and the plate is lifted by means of the lever system as before. The pins are now reinserted in the apertures of the valve stems after the valves have been replaced and the 35 springs are lowered by a reverse movement of the lever until their cups again engage with the bosses 18 when the device is finally withdrawn.

Having thus described my invention, what

I claim and desire to secure by Letters Patent is:

1. A device of the character described comprising a plate having a slot opening in an edge thereof, the edges of the slot having at the underside of the plate bevels tapering from said edge, and a lever connected with 45 the plate and adapted to elevate the same.

2. A device of the character described comprising a plate having a slot opening in an edge thereof, the parallel edges of the slot having at the underside of the plate 50 bevels tapering from said edge, and a lever connected with the plate and adapted to elevate the same.

3. A device of the character described comprising a spring-engaging plate, a lever 55 having an offset between oppositely directed arms, a pivot-connection between the free end of one of said arms and the plate, a prop pivoted at the juncture of the opposite 60 end of the same arm and the offset, and an operating handle pivoted at the free end of the other arm.

4. A device of the character described comprising a spring engaging plate, a lever having an offset between oppositely directed 65 arms, and having one arm pivoted to the plate, a prop pivoted to the lever intermediate its end, the pivot of the prop lying beneath the pivoted connection between the 70 lever and plate when the plate is in elevated position to lock the plate in such position and means for operating the lever.

In testimony whereof I have affixed my signature.

GEORGE MITCHELL.
